FRIDTJOV SEVERUD, OF FLUSHING, AND BENNETT MYERS, OF NEW YORK, N. Y.

FLOOR CONSTRUCTION

Application filed October 18, 1927. Serial No. 226,844.

Our present invention relates generally to concrete floor construction, and has particular reference to a method of laying so-called fireproof floors of concrete or similar masonry; coordinately, our invention relates to a structural beam designed for use in such a method.

Our invention relates primarily to short-span work in connection with which it has been customary heretofore to provide specially built forms not only beneath and around the steel beams defining the gaps to be floored, but also beneath the gaps themselves, this form work being designed to receive and support poured concrete or similar masonry until the latter has set. Such a procedure is obviously expensive in its requirement for special construction work in the designing and erection of the temporary forms. Such prior procedure has proven expensive also from the standpoint of quantity of concrete employed, and it has therefore been customary in many cases to employ so-called filler blocks which serve no useful supporting purpose and are merely laid upon the form work to occupy some of the space which would otherwise have to be filled in with the poured masonry.

It is one object of our present invention to provide a method of short-span floor construction wherein the necessity for temporary form work has been largely obviated, and whereby the amount of concrete employed has been reduced to a minimum. Coordinately, it is an object of our invention to provide a self-supporting and also self-centering structural beam designed eventually to form an integral part of the finished floor construction and at the same time fulfilling the function of both the temporary form work and obviating the necessity for employing blocks of no supporting utility.

More specifically, it is an object of our invention to provide a structural beam of concrete or similar masonry which is reinforced and so constructed as to be applicable in complementary relationship with a set of similarly constructed and employed beams (a) to initially seal the gap and thereby obviate the necessity for form work, (b) to define

the ceiling of the space beneath, (c) to support additional reinforcement and fresh concrete, (d) to minimize to the fullest extent the amount of fresh concrete to be poured, and (e) where desired, to define the upper 55 flooring surface.

One feature of our invention resides in the provision of a set of beams so constructed and arranged as to be arrangeable in complementary adjacency to fulfill the functions 60 outlined above. In a preferred construction, the beams are so configured that their lower surfaces complement each other to seal the gap and to define the ceiling beneath; the upper portions of the beams meanwhile providing a channelled construction which is designed to accommodate additional reinforced or unreinforced concrete.

A particular feature lies in so constructing the complementary beams that the freshly 70 poured concrete will arrange itself in such conjunction therewith as to provide a series of T sections whose desirable characteristics of strength are well known.

Another feature of our invention lies in 75 providing a beam whose construction and manufacture are simple in nature and whose self-supporting and self-centering characteristics are of the highest possible character with respect to size and amount of material 80 employed. In one form of our invention, the beam is a hollow or tubular structure having two substantially vertical reinforced stiffening webs; in a preferred form, the beam embodies only one stiffening web and is designed 85 for complementary employment with a similar juxtaposed beam to form a two-part tubular structure.

One of the features of our invention resides 90 in constructing the beam of substantially trapezoidal cross-section, thereby permitting the achievement in a simple manner of the functions outlined.

For the attainment of the foregoing objects and such other objects as may hereinafter appear or be pointed out we have illustrated several forms of our invention in the accompanying drawings in which—

Fig. 1 is a plan view of a portion of a steel 100

structure with the floor construction of the present invention in course of construction;

Fig. 2 is a cross-sectional view taken substantially along the line 2—2 of Fig. 1;

5 Fig. 3 is a cross-sectional view at right angles to Fig. 2 and taken substantially along the line 3—3 of Fig. 1;

Fig. 4 is a diagrammatic view showing one 10 step in the process of manufacturing a preferred form of beam;

Fig. 5 is a view similar to Fig. 4 showing another step in said process; and

15 Fig. 6 is a cross-sectional view of a preferred form of structural beam embodying the features of our invention.

20 In Figure 1, we have illustratively shown four columns 10, 11, 12, and 13, structural steel beams 14, 15, 16, and 17 extending between the columns, and structural steel beams 2. 18 and 19 extending between the beams 14 and 16. The arrangement of these steel columns and beams is merely illustrative, and provides three adjacent short-span areas or gaps which are to be floored.

25 In Figure 2 we have shown the steel beam 18 in cross-section, and our invention calls for the usual provision of the temporary form work beneath and around this beam to render the floor construction fireproof. The temporary form work comprises the supporting hooks or wires 20 and 21, the upper ends extending about the upper flange of the beam 18 and the lower ends passing around and supporting a series of wooden blocks 22.

30 Constructed upon the blocks 22 is the form work which is obviously of substantially U-shaped cross-section comprising the bottom boards 23, the side boards 24 and 25, and the outwardly disposed top boards 26 and 27.

35 The bottom boards 23 are spaced from the bottom flange of the beam 18 by means of suitable spacing elements, it being understood that the concrete when poured into the form will completely embed and thereby render fireproof the steel beam 18.

40 Heretofore it has been customary to extend this form work across the entire gap, i.e., between the beam 18 and the beams 15 and 19 on opposite sides thereof. In accordance 50 with our present invention, such additional form work is unnecessary. Instead, a series of reinforced concrete beams, of a self-supporting and also self-centering nature, are made to span these gaps.

45 In Fig. 6 a substantially horizontal top plate 32 is spaced from a substantially horizontal bottom plate 33, and a single substantially vertical reinforced stiffening web 34 extends between one edge of the top plate 32 and a medial portion of the bottom plate 33. Obviously, two beams constructed as in Figure 6 when arranged in juxtaposed relationship will form a composite beam.

55 A set of beams as shown in Figure 6 has 65 been illustrated in Figure 1 in the course of

application across the gaps to be floored. Thus, the gaps defined by the steel beams are being initially sealed by placing across them, in side by side adjacency, a number of beams constructed as shown in Figure 6. Obviously, alternate beams are oppositely arranged so that the resulting composite floor construction embodies a series of spaced channels which extend downwardly to the abutting bottom plates 33.

75 In Figure 2 we have shown the manner in which the beams are supported at their ends upon the wooden blocks 26 and 27 forming the upper part of the form work about the steel beam 18.

80 After the entire gap has been completely sealed by laying a sufficient number of beams across, freshly prepared concrete or similar masonry is poured onto and about the steel beam 18, and also into the channels presented by the composite floor construction initially applied. The latter is sufficiently strong to support the necessary laborers, etc., and the freshly poured concrete, and if desired, additional strips or bars of reinforcing may be 85 laid in the channels before the concrete is poured. Similarly, suitable reinforcing strips or bars may be applied transversely across the upper flange of the beam 18 before the concrete is poured so as to take care of the 90 negative moment along this line.

95 We have found it advantageous to bevel the ends of the concrete beams, as shown in Figure 2, so as to facilitate the pouring of concrete into the form about the steel beam. It is 100 frequently desirable also to seal these beveled ends with plates or the like, to prevent waste of concrete which may find its way into the interior thereof.

105 The concrete will be poured to at least the level of the upper surfaces of the concrete beams. Where desired, this amount of pouring will be sufficient, and the floor can then be finished off by the application of any desired layer of cement or the like. When desired, the concrete may be poured not only to the level of the upper surfaces but also slightly beyond, as shown in Figures 2 and 3, and it will be noted that a unitary floor construction results wherein the initially laid concrete beams are integrally embodied. It will also be noted that the poured concrete arranges itself in such relationship to the top plates as to provide T sections and thereby affords a 110 maximum amount of supporting strength to the completed floor.

115 In Figure 3 we have shown an auxiliary beam 35 which is illustrative of a type which may be employed whenever a slight gap still remains to be sealed adjacent to one of the steel beams. Thus, in Figure 3, the form work about the steel beam 11 embodies the top board 36, and the extreme edge 37 of the closest concrete beam 38 falls slightly short of the outer edge of the board 36. The applica- 120

tion of an additional concrete beam of the usual construction would be impractical, and accordingly, the small auxiliary concrete beam 35 is employed. This beam has a horizontal reinforced plate which aligns itself with and thereby complements the other horizontal plates, and a single vertical stiffening web extending upwardly to the level of the upper surfaces of the other concrete beams.

5 Obviously, the auxiliary beam 35 may be constructed in a variety of ways for fulfilling the same function.

After the unitary floor construction has set, it will be understood that the form work 15 about and beneath the steel beams is removed in the usual manner and the ceiling, as well as the construction in general, is finished off in the usual manner.

In Figures 4 and 5 we have shown a preferred method of constructing the beams of Figure 6. A suitable mold 39 is provided, into nesting relationship with which a complementary mold member 40 is designed to move. The steel reinforcing 41 is first applied to the mold 39 and properly positioned from the surfaces thereof; thereupon concrete 42 may be poured to approximately the level shown in Figure 4; and when the mold member 40 is then brought down into the 30 position shown in Figure 5, the plastic concrete will spread out as shown in Figure 5 and harden into the reinforced structure of Figure 6.

It will be understood that wherever the 35 term "concrete" has been employed herein, any similar type of poured masonry is intended to be included, since our invention is obviously not limited to the material technically and strictly known as "concrete." Furthermore, our invention is applicable to 40 an equally advantageous degree in the type of construction wherein steel beams are dispensed with and reinforced concrete beams are employed. In such an event, the form 45 work which we have herein illustrated as depending from the steel beams would be shored from beneath, but it would still embody the elements 26 and 27 upon which the ends of our structural beams rest.

50 It will be obvious that many changes in the details herein described and illustrated for the purpose of explaining the nature of our invention may be made by those skilled in the art without departing from the spirit 55 and scope of the invention as expressed in the appended claims. It is therefore intended that these details be interpreted as illustrative and not in a limiting sense.

Having thus described our invention and 60 illustrated its use, what we claim as new and desire to secure by Letters Patent is—

1. A flooring block substantially U-shaped in cross-section with one arm of the U extended beyond the base of the U.
- 65 2. A flooring block substantially U-shaped

in cross-section with one arm of the U extended beyond the base of the U, said arms, base, and extension being of reinforced concrete.

In witness whereof, we have signed this 70 specification this 14 day of October, 1927.

FRIIDTJOV SEVERUD.
BENNETT MYERS.
